(57) **CLAIM**

The ornamental design for a portable electric hammer drill, as shown and described.

DESCRIPTION

FIG. 1 is a front perspective view of the portable electric hammer drill according to the present invention;

FIG. 2 is a rear perspective view thereof;

FIG. 3 is a first side view thereof;

FIG. 4 is a second side view thereof;

FIG. 5 is a front end view thereof;

FIG. 6 is a rear end view thereof;

FIG. 7 is a top view thereof; and,

FIG. 8 is a bottom view thereof.
